ATTORNEY

UNITED STATES PATENT OFFICE.

MEARLE A. WILFORD, OF RIVER FALLS, WISCONSIN.

LADDER.

Application filed April 18, 1921. Serial No. 462,106.

To all whom it may concern:

Be it known that I, MEARLE A. WILFORD, a citizen of the United States, residing at River Falls, in the State of Wisconsin, have 5 invented new and useful Improvements in Ladders, of which the following is a specification.

The present invention contemplates the provision of a step-ladder wherein metallic 10 rungs are combined with wooden sides or stiles in the production of a ladder that possesses the desired stability, and is also exceptionally light in comparison to its strength.

One of the chief characteristics of the invention resides in the manner of associating the rungs with the sides of the ladder, so as to prevent the rungs from being casually separated from said sides, which insures safety in use of the ladder.

20 More specifically stated, the invention contemplates the provision of metallic rungs, which terminate to provide prongs adapted to penetrate the sides of the ladder and have their ends clinched against the outer side 25 thereof.

The nature and advantages of the invention will be better understood when the following detailed description is read in connection with the accompanying drawing, the 30 invention residing in the combination, construction, and arrangement of parts as claimed.

In the drawing forming part of this application, like numerals of reference indicate similar parts in the several views and wherein:

Figure 1 is a view in elevation of the ladder constructed in accordance with my invention.

40 Figure 2 is a sectional view taken on line 2-2 of Figure 1.

Figure 3 is a fragmentary edge elevation.

Figure 4 is a view of one of the rungs.

Referring to the drawing in detail, 10 indicates the opposed sides of the ladder, which are connected together by rungs 11. The sides 10 are preferably constructed of wood, while the rungs 11 are constructed

from metal to provide a ladder possessing strength and rigidity. While the rungs may 50 vary in cross sectional configuration, they are preferably of hollow or tubular construction, the diameter of the rungs depending upon the size of the ladder as a whole. The rungs 11 are bifurcated at their ends providing inner spaced parallel walls and inclined walls tapering from the outer end of the spaced parallel walls to provide prong 13 and defining thereby outwardly and oppositely inclined spreader walls, which penetrate the sides 10 of the ladder and have their ends subsequently bent or clinched against the outer surface of said sides. In addition to the fact that each end may be provided with any number of prongs, these 65 prongs may also vary in length according to the thickness of the sides 10. Manifestly, I have provided a ladder which eliminates the danger of a rung breaking or separating itself from the sides 10 thereby insuring 70 safety in use of the ladder.

While it is believed that from the foregoing description the nature and advantages of the invention will be readily apparent, I desire to have it understood that I do not 75 limit myself to what is here shown and described, and that such changes may be resorted to when desired as fall within the scope of what is claimed.

What I claim is:

A ladder comprising opposed side members constructed of wood, metallic rungs of tubular formation having their ends bifurcated to provide inner spaced parallel walls and inclined walls tapering from the outer end of the spaced parallel walls defining spreader walls thereby, each bifurcated end constituting prongs piercing one of the side members, said prongs being deflected outwardly and terminating beyond the outer 85 surface of each side member with the end of each prong bent against the surface of the respective side member.

In testimony whereof I affix my signature.

MEARLE A. WILFORD.
